SAFETY DEVICE FOR GAS OVENS

Thomas Esta Phares, Shelbyville, Ind., assignor
to Chambers Corporation, a corporation of
Indiana

Application April 14, 1949, Serial No. 87,547

10 Claims. (Cl. 126—42)

1

This invention relates to an ignition device for ovens in gas-cooking stoves, and has particular reference to means to prevent ignition of the gas burner when the oven door is closed.

The manual means for igniting the gas burner is generally similar to that described in the co-pending application of John E. Chambers, Serial No. 72,659, filed January 25, 1949 now assigned to the same assignee. It consists essentially of an electrical circuit closed automatically when the gas valve is opened to produce a spark adjacent the gas burner.

The present invention is concerned primarily with means for preventing the opening of the gas valve when the oven door is closed. This structure is of particular importance in connection with a gas oven because the oven is an enclosed space in which a discharge of unburned gas can create a hazardous explosive mixture with the contained air.

In the oven constructed in accordance with the present invention, the oven bottom plate, which is located above the burner, has an opening adjacent to its front edge through which the burner and its flame are plainly visible when the oven door is open. If, for any reason, the gas is not ignited immediately when the valve is opened, the failure of the ignition system is apparent, and the gas can be ignited with a match. The open door precludes the possibility of an explosive mixture with the contained air.

The structure of the present invention by which the above advantages are attained will be described in the following specification, taken in conjunction with a preferred illustrative embodiment shown in the accompanying drawings, in which:

Figure 1 is a cross sectional view showing the arrangement of parts when the oven door is closed;

Fig. 2 is a cross sectional view, similar to Fig. 1, showing the arrangement of parts when the door is open;

Fig. 3 is a fragmentary cross sectional view showing the bottom portion of the oven door and the associated stove structure;

Fig. 4 is a fragmentary cross sectional view of the upper portion of the oven door and the mechanism for controlling the flow of gas;

Fig. 5 is a cross sectional view taken along the line 5—5 of Fig. 4, showing the mechanism for holding the gas control valve against rotation; and

Fig. 6 is a diagrammatic perspective view of the safety lock bar and associated mechanism.

2

In the drawings, the reference numeral 2 indicates the outside steel front of the gas cooking stove. The front opening of the oven is closed by an insulated door 3 secured in closed position by a latch 4. The catch member 5 has a stem 6 projecting through front 2 and secured to the upper portion of a flat plate 7 by means of a nut 8 threaded on the stem. The plate covers the entire area of the front of the oven and has an opening aligned with the opening in front wall 2. The lower edge of plate 7 is secured to a plate 9 forming the bottom of the oven. A pair of vertically aligned studs 10 is secured to plate 7 with their headed ends projecting towards the front of the stove. A safety lock bar 11 provided with a pair of elongated slots 12 is mounted in front of plate 7 with one slot 12 embracing each stud 10.

The top edge of bar 11 is bent rearwardly at right angles, as indicated at 13, and a plate 14 secured thereto has its free end engaging an abutment 15 formed on the edge of a disk 16 rigidly mounted on a shaft 17 operatively connected to the gas valve 17'. Shaft 17 including disk 16 must be rotated to open the gas control valve and thus permit the flow of gas to the oven burner. Disk 16 has a notch 18 on its edge opposite abutment 15.

As described in the co-pending Chambers application hereinabove identified, a housing 19 seats in notch 18 and prevents disk 16 and shaft 17 from rotating. Tilting of the housing by application of thumb pressure on the lever 19' serves to move it out of engagement with the notch and permits rotation of the shaft. The housing carries a contact member 20' which serves to close a switch 20 upon movement of the housing slightly beyond the region of its engagement with the notch. When the switch is closed an electrical circuit 22 is energized and a spark is produced adjacent the oven gas burner 23. The spark ignites the burner and the electrical circuit is then opened by releasing the tilting pressure on the housing.

The safety lock bar 11 carrying plate 14 prevents ignition of the burner when the oven door is closed by engagement of the plate with abutment 15, because the plate cannot be removed from such engagement without opening the oven door. While the oven door is closed, the engagement of plate 14 with abutment 15 prevents rotation of shaft 17 to move the gas control valve from closed position, and thereby prevents the flow of gas to the burner.

The lower edge of door 3 is hinged adjacent the

bottom of the front opening of the oven, as indicated at 24. A door stop 25 is secured at its upper end 26 to the inside of the door, and its lower end 27 is pivotally secured to an oven door stop rod 28. Rod 28 extends through oven bottom 9 almost to the bottom of front plate 2. A coiled compression spring 29 encircles rod 28 below bottom 9, and is retained on the rod by means of a nut 30 and washer 31. When the oven door is opened the lower end 27 of stop 25 moves upwardly, as indicated in Fig. 2, thereby pulling up the rod and compressing spring 29. The spring will not close the oven door by itself but will assist in closing it and will hold it in closed position.

Door stop 25 has its outer edge 31 cam shaped, so that the portion engaging the bottom edge of safety lock bar 11 when the door is closed (as shown in Fig. 1) is at a greater height above the oven bottom than the portion engaging it when the door is open (as shown in Fig. 2). When the oven door is closed, edge 31 keeps bar 11 in its uppermost position, in which position plate 14 engages abutment 15 to prevent rotation of disk 16, thereby making it impossible to turn on the gas. When the oven door is opened, cam surface 31 permits bar 11 to slide down, and plate 14 drops out of engagement with abutment 15 so that disk 16 may be rotated to open the gas control valve. Slots 12, which embrace studs 10, permit sufficient movement in the safety bar to clear abutment 15.

Although gravity alone is ordinarily sufficient to cause the safety bar to drop as the portion of edge 31 of door stop 25 engaging the lower edge of the safety bar moves downwardly, a spring 32 is provided to exert downward pressure on plate 14 to eliminate any possibility of the safety bar failing to move out of engagement with abutment 15 when the oven door is opened.

A baffle plate 33 extending in a horizontal plane over burner 23 protects the burner from gusts of wind when the oven door is opened and also protects the cooking area of the oven from the direct flames from the burner. The baffle plate stops short of the front wall of the oven so as to leave an opening 34 between its front edge and plate 7 through which the burner may be observed when the oven door is open. Accordingly, if the oven door is opened and handle 35, rigidly secured to shaft 17, is turned to cause gas to flow to the burner, it will be immediately apparent if the ignition means fails to ignite the gas. In case of failure of the ignition means, the gas can be turned off until the gas accumulation in the oven is dissipated, and then the gas may be ignited by means of a match which may be inserted through opening 34 when the door is open. A cover plate 36, bolted to the lower edge of door 3, closes opening 34 when the oven door is shut so that flames from burner 23 cannot shoot into the cooking compartment of the oven.

The oven is provided with a damper 37 in its bottom wall and another damper 38 in its rear wall. A damper control rod 39 has one end 40 (Figs. 1 and 5) rotatably secured in disk 16 and its other end 41 pivotally secured to one end of a bell crank 42. A link 43, secured at one end to the pivot 44 of the bell crank, moves upwardly to open damper 37 when disk 16 is rotated by the rotation of shaft 17 when the gas is turned on. The exact degree of opening of damper 37 depends upon the degree of rota-

tion of disk 16. The other end of bell crank 42 is secured to a second damper control rod 45. The other end of rod 45 is secured to a link 46 which is secured to damper 38. When rod 39 moves bell crank 42 to open damper 37, rod 45 moves link 46 to open damper 38. When damper 37 is closed, damper 38 is also closed.

From the foregoing it will be seen that I have devised simple and efficient means for preventing ignition of an oven gas burner when the door is closed and for visually observing the burner when the door is open, thereby providing an ample factor of safety for igniting gas oven burners electrically.

Although I have described a preferred embodiment of my invention in considerable detail, it will be understood that the description thereof is intended to be illustrative, rather than restrictive, as many details may be modified or changed without departing from the spirit or scope of the invention. Accordingly, I do not desire to be restricted to the exact structure described.

I claim:

1. In an oven, a gas burner, a valve rotatable to control the flow of gas to said burner, a disk rotatable with said valve, a safety lock bar slideable in a vertical direction, said bar when in its uppermost position engaging said disk to prevent rotation of said valve from closed position, a hinged door adjacent the front of said oven, and a door stop movable with said door, one edge of said door stop being cam-shaped, the lower end of said safety lock bar engaging said cam-shaped edge to position said bar, said cam-shaped edge holding said bar in its uppermost position when said door is closed.
2. In an oven, a door, a gas burner, a valve rotatable to control the flow of gas to said burner, a disk rotatable with said valve, said disk having an abutment projecting therefrom, a safety lock bar engaging said abutment to prevent rotation of said valve when said valve and said door are closed, said safety locking bar being movable from engagement with said abutment only upon movement of said door to open position, and a door stop secured to said door, said door stop having an upper edge in the shape of a cam, said upper edge engaging the lower end of said locking bar and operable to move said safety locking bar upwardly when said door is moved to closed position, whereby said bar will engage said abutment when said valve is rotated to closed position.
3. In a gas cooking stove, an oven, a door hinged to said stove adjacent the front of said oven, a door stop movable with said door, said door stop having a cam-shaped edge, a safety lock bar mounted to slide in a vertical plane intersecting the plane of said door stop, the lower edge of said bar resting on said cam-shaped edge of said door stop whereby said bar is moved between an upper and a lower position as said door is moved between closed and open position, a gas burner in said oven, a valve controlling the flow of gas to said burner, and a disk rotatable with said valve, the upper end of said bar engaging said disk when said bar is in its upper position and said gas control valve is in its off position to prevent rotation of said disk and thereby prevent turning of said gas control valve from its off position when said oven door is closed.
4. In a gas cooking stove, an oven having a hinged door, a stop member secured to said door,

the portion of said stop member adjacent the front of said oven being positioned at a greater height above the bottom of said oven when said door is closed than when it is open, a safety lock bar operatively connected to said stop member, and a gas control valve for said oven, said valve including a manually operable means for opening and closing said valve, said bar being slidably mounted in a plane adjacent the front of said oven with its lower end riding on said stop member, said bar interengaging with said manually operable means for preventing opening of said gas control valve when the lock bar is in its uppermost position, to prevent the opening of the gas control valve.

5. In a gas cooking stove, an oven having a hinged door, a gas burner in said oven, a gas control valve for said burner, said valve including a shaft rotatable to regulate the flow of gas to said burner, a disk rigidly secured to said shaft and rotatable therewith, a peripheral abutment on said disk, a safety lock bar engageable with said abutment to prevent rotation of said disk when said valve is closed, and a door stop having an upper cam shaped edge engaging the lower end of said lock bar, said door stop being operatively connected to said door to hold said bar in said abutment-engaging position when said door is closed.

6. In a gas cooking stove, an oven having a hinged door, a gas burner in said oven, a gas control valve for said burner, said valve including a shaft rotatable to regulate the flow of gas to said burner, a disk rigidly secured to said shaft and rotatable therewith, a peripheral abutment on said disk, a safety lock bar engageable with said abutment to prevent rotation of said disk when said valve is closed, and a door stop connected to said door, said door stop engaging said bar to prevent its disengagement from said abutment when said door is closed.

7. In a gas cooking stove, an oven having a hinged door, a gas burner in said oven, a gas control valve for said burner, said valve including a shaft rotatable to regulate the flow of gas to said burner, a disk rigidly secured to said shaft and rotatable therewith, a peripheral abutment on said disk, a safety lock bar engageable with said abutment to prevent rotation of said disk when said valve is closed, a door stop movable with said door, said door stop engaging said bar to prevent its movement from said abutment-engaging position when said door is closed, and a spring urging said bar downwardly, said door stop being so shaped as to permit said bar to move downwardly out of engagement with said abutment when said door is moved to open position.

8. In a gas cooking stove, an oven, a door for said oven, a door stop movable with said door

and extending at right angles thereto, a plurality of dampers in said oven, a gas burner in said oven, a valve rotatable to control the flow of gas to said burner, said valve including a shaft rotatable to regulate the flow of gas to said burner, a disk operatively connected to said shaft and rotatable therewith, a safety lock bar engaging said door stop and held thereby against said disk to prevent rotation thereof from closed position when said door is closed, and a rod operatively connected with said disk and said dampers, said rod opening said dampers when said disk is rotated from closed to open position.

9. In a gas cooking stove, an oven, a door for said oven, a door stop movable with said door and extending at right angles thereto, a plurality of dampers in said oven, a gas burner in said oven, a valve rotatable to control the flow of gas to said burner, said valve including a shaft rotatable to regulate the flow of gas to said burner, a disk operatively connected to said shaft and rotatable therewith, a safety lock bar engaging said door stop and held thereby against said disk to prevent rotation thereof from closed position when said door is closed, said door stop being so shaped as to permit said bar to move from disk-engaging position when said door is opened, and means operated by rotation of said disk to open and close said dampers.

10. In an oven, a gas burner, a valve rotatable to control the flow of gas to said burner, a disk rotatable with said valve, a safety lock bar slideable in a vertical plane, said bar having a lateral extension at its upper end engaging said disk to prevent rotation of said valve from closed position when said bar is in its uppermost position, a hinged door adjacent the front of said oven, and a door stop movable with said door, one edge of said door stop being cam-shaped, the lower end of said safety lock bar engaging said cam-shaped edge to position said bar, said cam-shaped edge holding said bar in its uppermost position when said door is closed.

45 THOMAS ESTA PHARES.
